UNITED STATES PATENT OFFICE.

FREDERICK CROMPTON LAKE, OF RAYNE, COUNTY OF ESSEX, ENGLAND.

MACHINE FOR SEWING THATCH.

SPECIFICATION forming part of Letters Patent No. 391,251, dated October 16, 1888.

Application filed March 21, 1887. Serial No. 231,719. (No model.) Patented in England March 29, 1886, No. 4,385; in Belgium January 8, 1887, No. 75,884, and in Austria-Hungary April 9, 1887, No. 5,197 and No. 70,987.

To all whom it may concern:

Be it known that I, FREDERICK CROMPTON LAKE, a subject of the Queen of Great Britain, residing at Rayne, in the county of Essex, 5 England, agricultural-implement maker, have invented a new and useful Improvement in Machines for Sewing Thatch, (for which I have obtained Letters Patent in England, dated March 29, 1886, No. 4,385; in Austria-Hun- 10 gary, No. 5,197 and No. 70,987, dated April 9, 1887, and in Belgium, No. 75,884, dated Janu- 15 ary 8, 1887,) of which the following is a specification.

Referring to the accompanying drawings, 15 Figure 1 is a front view, Fig. 2, a back view, and Fig. 3 an end view, of a machine constructed in accordance with this invention. Figs. 4 and 5 are respectively end view and top view of a fluted roller, which is in some cases em- 20 ployed for the purpose of assisting the feed; and Figs. 6 and 7 are views of a contrivance for regulating the tension of the string. Fig. 25 8 is a view of the driving end of the machine, with a portion of the driving-wheel removed or broken away. Fig. 9 is a cross-section showing the mechanism for actuating the hook and needle spindles, with the needle shown down below the table-plate and the loop of the string over the hook. Fig. 10 is a similar view 30 with the mechanism in a different position. Fig. 11 is a view of the hook. Fig. 12 is a de- 35 tached view showing the relation of the guide- spring to the needle and the manner in which the string is held away to allow the hook to enter between it and the needle.

This invention relates to improvements in the construction of machines for sewing thatch, 40 by means of which such operation can be effected in a more convenient and economical manner than by machines as ordinarily constructed.

I am aware that machines for sewing thatch have been known and used for many years; 45 but the use of such machines has always been attended by certain disadvantages which are obviated by the improvements constituting the subject of the present invention. For instance, in a machine for which Letters Patent No. 2,419, dated the 21st of September, 1866, 50 were granted in England to George Onley

Gooday, the needles are arranged to work down- 55 ward through the straw, and the sewed thatch as it comes from the machine is rolled up into bundles; but, owing to the position of the needles, the stitches have been so formed as to cause the lengths of thatch as they come from the machine to be rolled up in a direction contrary to that which would leave the right side uppermost when unrolled for use. It has consequently been necessary, in order to have 60 the thatch ready for immediate use, to reroll the lengths in the reverse way. In addition to obviating the disadvantage lastly referred to, the said improvements allow of a clear ob- 65 servation of the formation of the stitches, thus enabling the attendant at once to perceive any irregularity in the working of the machine.

I will now proceed to describe my said in- 70 vention with reference to the accompanying drawings, in which the same letters of refer- ence indicate like parts in all the figures.

Fig. 1 is a front view; Fig. 2, a back view, and Fig. 3 an end view.

The frame A of the machine is constructed in any suitable manner, but is, by preference, 75 of the form shown in the said drawings. Within suitable bearings, at the upper part of the frame, is arranged a shaft, B, which carries the hooks C, for completing the stitches, as hereinafter described. The said hooks are 80 pivoted to levers attached to sockets keyed on to the said shaft. A spring, u, is arranged be- 85 tween the said lever and the upper end of the hook above the pivot, in order to facilitate the taking of the loop of string from the needle and the retaining of the same until the time arrives for its release. At the lower part of 90 the frame are arranged the bearings for the needle-shaft D. The needles E are connected with the top ends of a vertically-reciprocating T-piece, F, the lower end of which is con- 95 nected to a lever, G, on the shaft D.

H H are guide-rods for the T-piece F.

I I are feed drums or rollers, over each pair 95 of which is passed an endless spiked band, i, which bands are caused to travel by the revo- lutions of the drums or rollers, so that the spikes projecting through the table-plate J will force the straw and sewed thatch forward when the needles are clear of the same. The 100

said drums or rollers are mounted on the shafts K and L. In some cases, in addition to the said drums or rollers I, I arrange a fluted roller, I', above the feed-board J', for the purpose of further regulating the feed. Fig. 4 is a detached end view of the said roller, and Fig. 5 is a top view of the same. The said roller is divided into two or more parts, and within the space or spaces between the said parts I mount loosely on the spindle a metal finger or fingers, w. The said finger or fingers will allow of the passage of the straw or other material to the needles, while the position thereof will prevent any of the material from being carried too far round by the roller I'. The said fingers are of such a length as to come into contact with the feeding-board J', whereby they are prevented from turning in the wrong direction. The said roller I' is mounted in suitable bearings, and driven by the shaft L, through the medium of an endless band, as shown, or in any other preferred way.

N is the driving-shaft, which is actuated by any desired and suitable power. The said shaft 25 is mounted in the bracket n. On the shaft N is the disk O, or other equivalent contrivance, which is connected to the arm or lever P on the needle-shaft by the connecting-rod R, in order to effect the desired oscillating motion of the 30 said shaft. To a lever attached to the strap of the eccentric S is connected an arm or crank on the spindle B in such a manner that on the shaft N being revolved the spindle B will be caused to rock. Also, on the said shaft N is 35 mounted the eccentric T, to the strap of which is attached a lever, the opposite end of which is pivoted to the link U. A pawl on the latter causes the ratchet V to be revolved at intervals. X is a contrivance for obtaining the 40 proper tension of the string.

Y are plates, between which and the table-plate J the straw is pressed when being sewed, the needles passing through apertures in the said plates.

45 Figs. 6 and 7 are detached views of the tension contrivance X, which is constructed as follows: To a plate, x, in which are formed a number of perforations, are attached two pins, x', on each of which is mounted a collar, x'', which is pressed against the said plate by the action of a spring arranged between it and a nut at the end of the pin, the force with which the said collar x'' is pressed against the plate being regulated by screwing or unscrewing 50 the nut. In arranging the string in connection with the said tension device it is first passed through two or more apertures in the plate x and then between the latter and the collar x'', whence it passes to the needle.

55 60 The action of machines constructed as here-

1 inbefore described is as follows: The string, having been suitably arranged on the tension contrivance, is passed through the eyes of the needles. On the shaft N being revolved a 65 rocking motion is transmitted to the spindle D, whereby the needles are moved upward through the table-plate J and the straw between the same and the plates Y and through the apertures in the latter. The spindle D then begins to rock in the oposed direction, thereby 70 causing the needles to return, and the string at the sides thereof loops out. At this movement the shaft B is rocked, so as to bring forward the hooks C, which respectively catch one of the loops formed by the needles, being 75 assisted in so doing by the guide-springs z, around which the string passes, and by which it is held away from the needle, as indicated in Fig. 12, so that the hook C may freely enter between the two. Under the most favorable 80 circumstances and with selected string, the string may be dispensed with, but under ordinary circumstances it will be found to be of great assistance. The hooks then move back and the needles descend below the table-plate 85 J. The shafts K and L are then revolved sufficiently to advance the straw the distance of a stitch, and the needles again move upward and pass through the loops which have been released from the hooks, thus forming fresh 90 stitches.

In Fig. 10 the needles are shown as having passed up through the apertures in the table-plate and through the loop on the hook C, which loop is shown about to slip off the said 95 hook. The needle will then commence to move downward, and the hook, moving forward at the same time, will catch the string near the eye of the needle, and the string so caught by the hook forms another loop, and so on.

What I claim is—

1. In machines for sewing thatch, the combination of the feed-board J', the fluted feeding-roller I', and the fingers w, arranged and operating substantially as and for the purpose 105 set forth.

2. In machines for sewing thatch, the combination of the shaft B, hook C, shaft D, needles E, the tension device X, feed-roller I', table-plate J, the plates Y, driving-shaft N, and 110 mechanism, substantially as described, for connecting the driving shaft with the other parts to operate the same, substantially as described.
